UNITED STATES PATENT OFFICE.

REUBEN B. BENJAMIN, OF CHICAGO, ILLINOIS, A SIGNOR TO BENJAMIN ELECTRIC MANUFACTURING COMPANY, OF CHICAGO, ILLINOIS, A CORPORATION OF ILLINOIS.

PLURAL LAMP-SOCKET.

No. 852,491.

Specification of Letters Patent.

Patented May 7, 1907.

Application filed October 1, 1904. Serial No. 226,800.

To all whom it may concern:

Be it known that I, REUBEN B. BENJAMIN, a citizen of the United States, residing at Chicago, in the county of Cook and State of Illinois, have invented new and useful Improvements in Plural Lamp-Sockets, of which the following is a full, clear, concise, and exact description, reference being had to the accompanying drawings, forming a part of this specification.

My invention relates to plural lamp sockets.

One of the objects of my invention is to provide a simple and highly efficient socket adapted to mechanically support and electrically connect a pair of electric lamps in an end to end position, and to provide suitable terminals upon the socket adapted to connect the terminals of said lamps in circuit, through the medium of the terminals of an ordinary electric lamp socket.

The other novel features of my invention will more fully appear from the accompanying description of the drawings, in which I have illustrated one method of embodying my invention in a practical structure.

Figure 1 is a side elevation of my improved socket showing the interlocking inclosing casing; Fig. 2 is an end view of my invention; Fig. 3 is a view taken on the line 3—3 of Fig. 2; Fig. 4 is a view taken on the line 4—4 of Fig. 1; Fig. 5 is a detail view to be more fully hereinafter described.

Referring to the drawings by reference characters, in which like numerals are used to designate like parts in the several figures, I provide a base 1, preferably in one piece and made of porcelain or other suitable insulating material, which carries a screw threaded shell 2, or a similar device for making connection with the outer contact of an electric lamp socket, and a center contact 3, which in this instance is shown as a strip or plate, although any equivalent construction may be adopted. The ends of the plate or strip 3 extend through an aperture 5 in the base and are turned up and centrally disposed within the lamp receiving shell 6, to form the center contacts for the lamps, the shells 6 forming the ring contacts therefor.

Any equivalent devices may be provided for mechanically supporting and electrically connecting the lamps in circuit in lieu of the shells 6, 6. The shells are preferably mount-

ed directly upon the base 1, by bolts or screws 7, 7, passing through the base and engaging said shells, an aperture being cut in the bottom of each of said shells to permit the center contacts 4, 4, to engage the center contacts of the lamps, as shown in Fig. 2. The shell 2 is preferably mounted in position upon the base 1, by a U-shaped plate or band 8, the ends of which extend through apertures in the shell 2, and are bent back upon themselves, as shown in Fig. 4. The band is engaged by the screws or bolts 7, whereby the lamp receiving shells are electrically connected with one terminal of the plug.

Any suitable insulating material, as the fiber lining 9, is provided for insulating the lamp receiving shells 6, 6, from the metal inclosing casing. This lining consists of two rings of insulating material, preferably having an outwardly extending flange 11, formed thereon adapted to retain said lining in position between the shells 6, 6, and the casing 10. The casing 10 is preferably made of thin metal, and in the present instance consists of two members 12 and 13, adapted to telescope each other and provided preferably upon either side of the casing 10, with suitable bayonet joints or equivalent devices 14, 14.

In the present embodiment of my invention, an L-shaped depression 15 is formed in one of the members of said casing, adapted to accommodate a small projection 16 formed in the other member of the casing 10, as shown in Fig. 4, the depression 16 being carried into the L-shaped extension of the depression 15 when the members of the casing are slightly rotated, and thus lock the members 12 and 13 of the casing firmly together.

The means shown and described for locking the members of the casing together is a simple construction, and it will be understood that the same may be varied without affecting the present invention.

It will be seen that the portion of the base carrying the contacts 2 and 3, constitutes a plug attachment adapted to engage the terminals of an ordinary lamp socket, the terminals on the plug being connected with the terminals of the lamp holding devices. In order to connect the lamps in circuit, it is necessary to screw the plug portion of the device into the lamp socket, until the center

lamp contact 3 comes in contact with the central terminal of the socket, and as it is often desirable to have the two lamps of the cluster stand at a certain angle when the device is connected in circuit, this cannot be accomplished without partially unscrewing the plug portion of the device from the socket. This partial withdrawing of the plug portion of the device from the socket is apt to withdraw the central contact carried by the plug from engagement with the central contact of the socket. In order to overcome this objection, and in order to allow the plug portion to be inserted in the socket so as to permit the lamps to stand at any desired angle, I prefer to mount the strip 3 loosely on the base 1, to permit it to move longitudinally through said base 1, when the end of said strip constituting the center contact 3, comes in contact with the center contact of the lamp socket, a small coiled spring 17, being adapted to hold the center contact 3 in its extended position, as shown in Fig. 3, and to hold the contact 3 in engagement with the central terminal of the lamp socket, when the plug portion of the device is partially withdrawn therefrom, in order that the lamps may occupy the desired position as above described.

Any suitable spring may be substituted for the coiled spring 17, and I am aware that the detailed arrangement of the parts of my invention may be varied without departing from the spirit thereof, and I do not wish to limit myself to said details of construction further than is defined in the appended claims.

It will be noted that the center contact 3 of the plug extends longitudinally through the plug and has a bifurcated end, the prongs 4, 4, of which constitute the center terminals of the lamp sockets, a slot being provided in the upper end of the insulating base to accommodate these center contacts. The center contact is yieldingly mounted so that it may be slightly depressed as the plug is screwed into the socket, with which it is employed. The yielding mounting of the center contact performs an important function, since if the center contact were rigid, it would be necessary to swivel the plug to the insulating base or make other provision for the rotation of the plug independently of the twin socket. Unless the plug were so swiveled to the insulating base or a yielding mounting of the center contact be provided when the plug is screwed home and the center contact thereof is in contact with the contact of the socket, it would be impossible to slightly rotate the twin socket due to the fact that such a rotation would break the contact between the center contact of the plug and the center contact of the lamp. By the provision of the yielding mounting of the center contact, I am enabled to accomplish the same result. In twin plug sockets of this

class, the lamps are frequently arranged in the angle of a show-case or show-window or in other similar position where the position of the lamps is fixed and determined. If the center contact were rigid, it would frequently happen that when the plug was screwed home, the twin socket would occupy a position at an angle to that which it should properly occupy. In order to obviate this objection, it has heretofore been proposed to swivel the plug to the twin socket, so that the plug may be screwed home and the twin socket then moved independently to the proper position. By the employment of the yielding center contact, the plug and the twin socket may be slightly rotated to bring the lamps into the proper position without affecting the firm contact between the plug terminals and the contacts of the socket in which it is inserted. It will thus be seen that the yielding center contact performs an important function in a twin plug socket.

I am aware that yielding contacts have been employed in individual lamp sockets, but the function there performed and the result accomplished is entirely different from that of the present twin socket. It will be noted that the yieldingly mounted center contact passes through the center of the plug and insulating base, that the prongs upon the inner end thereof lie in a transverse slot in the insulating base, while the ring contact of the plug is connected with the ring contacts of the twin socket by means of a yoke, which passes around the periphery of the insulating base.

Having thus described my invention what I claim as new and desire to secure by Letters Patent is:

1. In a two-light electric lamp plug socket, the combination with an insulating base, of a pair of lamp receiving shells mounted thereon end to end and in substantial alinement, said insulating base having a transversely extending integral plug portion, suitable terminals carried thereon, and a cylindrical casing inclosing said lamp receiving shells and arranged longitudinally of the axis thereof and being formed upon one side to accommodate the passage of said transversely extending plug portion.

2. In a two-light electric lamp socket, the combination with an insulating base, of lamp receivers arranged end to end upon said base and adapted to support the lamps substantially in axial alinement, lamp contacts associated with said receivers, an inclosing cover or casing arranged longitudinally of the axis of the receivers, a suitable transversely extending plug formed integrally with said base and carrying terminals in electrical connection with the lamp contacts, and an insulating lining for said cover or casing arranged upon one side to accommodate the transverse passage of said plug.

3. In a two-light electric lamp socket, the combination with an insulating base, of lamp receivers arranged end to end upon said base adapted to support the lamps substantially in axial alinement, lamp contacts associated with said receivers, a separable two-part inclosing cover or casing arranged longitudinally of the axis of the receivers and having an opening on one side, and a suitable transversely extending plug formed integrally with said base extending through said opening and carrying terminals in electrical connection with the lamp contacts.
4. In a two-light electric lamp socket, the combination with an insulating base, of lamp receivers arranged end to end upon said base and adapted to support the lamps substantially in axial alinement, lamp contacts associated with said receivers, an inclosing cover or casing arranged longitudinally of the axis of the said receivers, a suitable plug formed integrally with said base carrying a ring terminal and a center terminal, said center terminal extending through said plug and having a bifurcated inner end forming the center lamp contacts, and means for connecting the ring terminal with the ring contacts of the lamps.
5. In a two-light electric socket, the combination with an insulating base, of lamp receivers arranged end to end upon said base and adapted to support the lamps substantially in axial alinement, lamp contacts associated with said receivers, an inclosing cover or casing arranged longitudinally of the axis of the receivers a suitable transversely ex-
- tending plug formed integrally with said base and carrying a ring terminal and a yieldingly mounted center terminal to accommodate the partial rotation of said plug in a socket, and means for electrically connecting the said ring and center terminals with the lamp contacts. 40
6. The combination with a twin or two-light socket, having a pair of lamp receiving shells mounted end to end, of a plug extending transverse thereto and having a ring contact and a center contact, the latter being yieldingly mounted to accommodate the partial rotation of the plug in a socket. 45
7. In a twin plug socket, the combination with an insulating base, of a pair of lamp receiving shells mounted upon opposite sides thereof, an integrally formed transversely extending plug portion of said base, a ring terminal and a center terminal on said plug portion, center contacts for the lamp receivers connected with the center contact on said plug, said center contacts resting in a transverse recess or slot in said insulating base, and a yoke passing around the periphery of said insulating base for connecting the ring terminal on the plug with said lamp receiving shells. 50
- In witness whereof, I have hereunto subscribed my name in the presence of two witnesses. 55
